UNITED STATES PATENT OFFICE.

GEORGE J. CLINE, OF GOSHEN, INDIANA.

SICKLE-GRINDER.

SPECIFICATION forming part of Letters Patent No. 448,473, dated March 17, 1891.

Application filed October 27, 1890. Serial No. 369,473. (Model.)

To all whom it may concern:

Be it known that I, GEORGE J. CLINE, a citizen of the United States of America, residing at Goshen, in the county of Elkhart 5 and State of Indiana, have invented certain new and useful Improvements in Sickle-Grinders, of which the following is a specification, reference being had therein to the accompanying drawings.

10 My invention relates to certain improvements in grinding-machines; and it consists in the novel construction and combination of parts, as hereinafter explained, and pointed out in the claim.

15 In the accompanying drawings, Figure 1 is a perspective view of my improved grinder. Fig. 2 is a broken sectional elevation of the same, and Fig. 3 is a detail plan view showing more fully the knife-table.

20 In the embodiment of my invention I suitably secure or bolt upon a support or base A by bolts and nuts a a U-standard B, between the upper free ends of which is arranged a bearing-block d, whose halves or sections d' 25 d' are clamped by bolts and nuts upon a journal or shaft b, itself journaled or bearing in said ends of said standard. One end of the shaft or journal b is angular and adapted to permit of the application thereto of a hand-

30 lever C for the manipulation of said bearing-block together with the grinder (presently described) in adjusting the latter to the knife for grinding or sharpening the knife.

e is the grinder, of emery or other suitable 35 material, preferably in the form of two truncated cones placed base to base and having its shaft e' hung or journaled in the lower free ends of the arms of a bifurcated bracket or hanger g, as at e'', the upper ends of said 40 arms being themselves hung or pivoted upon a journal or shaft k, journaled in the halves or sections of the bearing-block at the outer end of the latter.

Upon one end of the shaft or journal k is carried or supported the large toothed or cogged wheel h, having a crank or handle i for its rotation and geared to a pinion g', secured upon the shaft e' of the grinder e for the rotation of

the latter in effecting the grinding or sharpening of the knife.

50 The grinder e is yieldingly or elastically held to its work for its better operation in sharpening or grinding the knife by means of the spring D, one end of which is connected, as at l, to the bracket or hanger g and having its other end connected, as at l', to either of two hooks m, secured to the base or support A, permitting of varying the tension of the spring or compensating wear thereof.

Projecting from the forward side of the 60 standard B is a U or bail shaped support f, to which is secured a cushion f', against which bracket or hanger g normally rests.

E is the stepped table, secured upon the base or support A for supporting the knife 65 while being ground, having the upper surface of its upper step inclined outward and downward to properly dispose the knife to the grinder, the inner edge of said table having a recess e³, corresponding with the contour 70 and adapted to receive the salient edge of the grinder in order to bring it (the grinder) in engagement with the knife.

F is a cam-lever held upon the lower step 75 of the table E by a bolt and nut f² and adapted to engage and clamp the knife down upon the table, as shown.

Having thus fully described my invention, what I claim, and desire to secure by Letters Patent, is—

80 The grinding-machine having journaled upon a shaft or journal supported between the upper ends of a standard a bearing-block whose free end bears a journal or shaft carrying a handled wheel, in combination with a 85 bracket or hanger carrying the grinder, whose shaft carries a pinion geared to said wheel, and the spring connected to said bracket and to the base of the machine, substantially as set forth.

90 In testimony whereof I affix my signature in presence of two witnesses.

GEORGE J. CLINE.
